UNITED STATES PATENT OFFICE.

ROBERT O. PEIRCE, OF BOSTON, MASSACHUSETTS.

SOFA AND LOUNGE BED.

SPECIFICATION forming part of Letters Patent No. 274,368, dated March 20, 1883.

Application filed February 10, 1883. (No model.)

To all whom it may concern:

Be it known that I, ROBERT O. PEIRCE, a citizen of the United States, residing at Boston, in the county of Suffolk and State of Massachusetts, have invented certain new and useful Improvements in Sofa and Lounge Beds; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and shows a perspective view. Fig. 2 is a detail view, and shows the side of the three-part hinge. Fig. 3 is a detail showing the side of the two-part hinge. Fig. 4 is a top view, partly in section, of the three-part hinge.

This invention has relation to devices for supporting the movable back or head-rest of a lounge or sofa bed; and it consists in the construction and novel arrangement of the double-plate or triple-plate hinge, having a spring-catch and registering locking-bearings, all as hereinafter set forth, and particularly pointed out in the appended claims.

In the accompanying drawings, the letter A designates the framing of the body portion of a sofa-bed.

B represents the movable back, and C a movable head-board connected to the end of the back.

D represents the movable bed-bottom of the main frame A.

E designates a rib or bearing extending along the back of the main frame A, and forming a part thereof.

F represents a three-part hinge, consisting of the middle plate, G, the front arm, G', and the back arm, G''. These arms are made in plate form, being designed to have their breadth at right angles to the parts to which they are secured, in order to give them great strength. The middle plate, G, and the arms G' G'' are formed with lateral flanges a, extending from their attachment edges and perforated for the passage of the fastening-screws. In the construction illustrated, the middle plate, G, is

firmly secured to the back bearing or rib, E, the front arm, G', to the bed-support D of the main frame, and the back arm, G'', to the movable back B. The arms G' and G'' of the 55 hinges F are connected to the supporting-plate G by means of pivots b b'. To the back arm, G'', is connected a spring-catch, c, the bearing end d of which engages a perforation, e', made in said back arm, near its inner end, eccentric to 60 the main pivot b, which connects said arm to the body-plate G. In this body-plate is made a perforation, e', at the same radial distance as the perforation e from the pivot b, and in relative position to register therewith when the 65 back B is in raised position. The spring-catch c then enters the perforation e', locking the arm G' to the middle plate, G, and holding the back in the elevated position.

H indicates a two-part hinge, which serves 70 to connect the head-board C to the back B. This hinge consists of two plate-arms, K and K', having perforated attachment-flanges f, and pivoted together at g. One of these arms is provided with a spring-catch, c', engaging a 75 perforation, h, in the arm, eccentric to the pivot. The other arm is also provided with an eccentric perforation, (indicated at h'), which, when the head-board is in raised position, registers with the perforation h and receives 80 the bearing end of the spring-catch, locking the head-board in raised position. These hinges are designed to be used in pairs in parallel relation, and the spring-catches of each pair are usually connected by a cord, z, which, 85 passing through openings in the back or head-board, serves to provide means for the disengagement of the spring-catch, allowing the back or head-board, as the case may be, to fall. These plate-hinges form strong braces 90 between the parts connected, and serve to hold them securely in relative position.

Having described this invention, what I claim, and desire to secure by Letters Patent, is—

1. A hinge consisting of plates pivoted together and provided with registering perforations and a spring-catch, substantially as specified.
2. A three-part hinge consisting of the 100 flanged middle plate, G, and the flanged arms G' G'', the eccentric perforations e' e, and the

- middle plate and back arm, G", and the spring-catch, substantially as specified.
3. The combination, with the body-frame of a sofa-bed and its back, of the three-part hinges F, having the registering perforations e e', and the spring-catches c, substantially as specified.
4. The combination, with the back of a sofa-bed and its head-board, of the two-part hinges H, having registering perforations and spring-catches, substantially as specified.

5. A sofa-bed having the movable back, and head-board connected to said back, and the flanged plate-hinges F H, the locking-springs, and cords, as specified.

In testimony whereof I affix my signature in presence of two witnesses.

ROBERT O. PEIRCE.
